United States Patent Office

Des. 227,309
Patented June 12, 1973

227,309

TELEPHONE INDEX

Clayton Austin Laughlin, Minneapolis, Minn., assignor to Standard Packaging Corporation, New York, N.Y.

Filed Sept. 23, 1971, Ser. No. 183,299

Term of patent 14 years

Int. Cl. D19—02

U.S. Cl. D74—1 C

FIG. 1

FIG. 5

FIG. 1 is a front perspective view of a telephone index according to the present invention in closed position;

FIG. 2 is a top plan view thereof;

FIG. 3 is a front elevational view thereof;

FIG. 4 is a side elevational view thereof; and

FIG. 5 is a front perspective view thereof in open position.

I claim:

The ornamental design for a telephone index, as shown and described.
